FURNACE

Original Filed May 11, 1922 2 Sheets-Sheet 2

Fig. II.

Inventor:
W. M. Duncan
By Cook, McCaulley, Atty.

UNITED STATES PATENT OFFICE.

WILLIAM M. DUNCAN, OF ALTON, ILLINOIS.

FURNACE.

Application filed May 11, 1922, Serial No. 560,118. Renewed January 29, 1926.

To all whom it may concern:

Be it known that I, WILLIAM M. DUNCAN, a citizen of the United States of America, a resident of Alton, in the county of Madison, 5 State of Illinois, have invented certain new and useful Improvements in Furnaces, of which the following is a full, clear, and exact description, reference being had to the accompanying drawings, forming a part of 10 this specification.

My invention relates generally to a furnace equipped with a mechanical stoker and other elements adapted to be associated therewith to provide for the combustion of 15 anthracite coal on a traveling grate, and particularly to a means for feeding said coal to said traveling grate.

Furnaces provided with mechanical stokers of the chain grate type are being used quite 20 extensively in connection with stills, and in the prior structures the coal receptacles were usually located at the front of the furnaces and at points beyond the end of the stills, the chain grate traveling under the coal receptacle and carrying the fuel toward the rear 25 of the furnace. It is not always convenient to so locate the chain grate with respect to the end of the still as to permit the front end of said chain grate to extend beyond said 30 still end, and this has been necessary in the past due to the fact that an outer coal receptacle must be provided which discharges the coal directly onto the inwardly moving grate. The furnace disclosed herein differs 35 essentially from the prior structures referred to in that the chain grate moves in a direction from the rear of the furnace to the front thereof, and the coal receptacle which discharges coal onto the grate is within the fire 40 box, and owing to this difference the furnace may be located at any place under the still, regardless of the proximity of the still ends.

In the preferred form of the invention, the coal receptacle is located within the fire 45 box at a point above the rear portion of the traveling chain grate, the grate passing under the coal receptacle at the rear of the furnace carries the fuel toward the front of said furnace, and a means is provided whereby the coal is conducted from an outer coal 50 receptacle to the coal receptacle within the fire box, from which said coal is discharged onto the chain grate.

Another advantage in having the coal receptacle located within the fire box arises 55 from the fact that the coal will be subjected directly to the heat of the fire box, and because of this fact said coal will be placed in an incandescent state before it reaches the traveling chain grate, and it will, therefore, 60 ignite immediately after leaving the receptacle.

With the foregoing and other objects in view, the invention comprises the novel construction, combination and arrangement of 65 parts hereinafter more specifically described and illustrated in the accompanying drawings wherein is shown the preferred embodiment of the invention. However, it is to be understood that the invention comprehends 70 changes, variations and modifications which come within the scope of the claim hereunto appended.

Fig. I is a vertical section of a portion of a still showing the furnace having a chain 75 grate associated therewith.

Fig. II is a section on line II—II of Fig. I.

In the drawings, 1 designates the side walls of a furnace on which a boiler B is 80 mounted, and 2 designates the tracks located between said side walls. Side frames 3 and 4 are provided with wheels which rest upon the tracks 2. A drive shaft 5, mounted in the side frames at the front of the grate, is 85 provided with a series of sprocket wheels 6 which lie between the side frames 3 and 4. An idle shaft 7 at the rear of the grate is provided with idle wheels 8. The wheels 6 and 8 constitute supporting elements for a 90 fuel carrier in the form of a traveling grate made up of numerous grate members A arranged in endless rows. Each grate member A is provided with two transverse openings adjacent to its ends for the reception of two 95 of the pivot rods 9. In the operation of the chain grate, the teeth on the sprocket wheels 6 engage the pivot rods 9 between the grate members A whereby the grate is driven in the direction indicated by the arrows in 100 Fig. I.

Located within the fire box of the furnace is a coal receptacle 10 (Fig. I), said coal receptacle being located immediately above the rear portion of the traveling grate. This 105 receptacle is open at the top to receive the

coal, and open at the bottom to permit the discharge of said coal onto the grate. A second coal receptacle 11 is located outside of the boiler B in a plane above the coal receptacle 10, and is provided with a discharge opening at the bottom thereof. The means for conducting the coal from the coal receptacle 11 to the coal receptacle 10 comprises an inclined tube 12 which communicates with the discharge opening in the coal receptacle 11 and passes through the boiler B in the manner illustrated in Fig. I of the drawings. The opposite ends of the inclined tube 12 may be brazed to the end wall and body wall of the boiler so that there will be no danger of the contents of the boiler leaking therefrom at the points where said tube passes through the boiler walls. The lower open end of the coal-conducting tube 12 is located immediately above the coal receptacle 10 within the fire box of the furnace, so that when coal is placed in the coal receptacle 11, said coal will pass through the tube 12 and be deposited in the coal receptacle 10, from which said coal will be eventually drawn by the traveling grate to be consumed in the usual manner thereon.

To provide a means for regulating the feeding of the coal to the coal receptacle 10

I employ a rotary feeder F which is of ordinary construction.

I claim:

In a furnace provided with a boiler, a traveling grate within the furnace fire box, a portion of said traveling grate being in vertical alinement with said boiler, a coal receptacle located in said fire box immediately above said grate, said coal receptacle having an open bottom permitting coal therein to be supported by the grate, a second coal receptacle outside of the furnace fire box and at an end of said boiler, the last mentioned coal receptacle being in a higher plane than the first mentioned receptacle, and a coal conducting member extended diagonally through the boiler, said coal conducting member being in communication with the second mentioned coal receptacle and said coal conductor terminating at the bottom of the boiler and at a point immediately above the first mentioned coal receptacle whereby coal may pass from the second mentioned coal receptacle through said coal conductor and be discharged into said first mentioned coal receptacle.

In testimony that I claim the foregoing I hereunto affix my signature.

WILLIAM M. DUNCAN.
